Primary Examiner—Carol Rademaker(74) *Attorney, Agent, or Firm*—Dykema Gossett PLLC(57) **CLAIM**

The ornamental design for a plastic container, as shown and described.

DESCRIPTION

FIG. 1 is a top, front perspective view of the plastic container of the present invention showing my new design;

FIG. 2 is a front elevational view thereof;

FIG. 3 is a rear elevational view thereof;

FIG. 4 is a left side elevational view thereof;

FIG. 5 is a right side elevational view thereof; and,

FIG. 6 is a top plan view thereof.

The broken lines shown in the drawings are for environmental purposes only and form no part of the claimed design.
